Primary Examiner—A. Hugo Word*Assistant Examiner*—Celia A. Murphy[57] **CLAIM**

The ornamental design for a plastic video cassette case, as shown and described.

DESCRIPTION

FIG. 1 is a perspective view of a plastic video cassette case showing my new design;

FIG. 2 is a perspective view thereof shown in an open position;

FIG. 3 is a front elevational view of FIG. 2;

FIG. 4 is a bottom plan view of FIG. 3;

FIG. 5 is a rear elevational view of FIG. 1;

FIG. 6 is a front elevational view of FIG. 1; and,

FIG. 7 is a top plan view of FIG. 1.
